United States Patent Office.

GEORGE WILKINSON, OF PROVIDENCE, RHODE ISLAND, ASSIGNOR TO GORHAM MANUFACTURING COMPANY, OF SAME PLACE.

Design No. 3,923, dated March 22, 1870.

DESIGN FOR FANCY SPOON AND FORK WORK

The Schedule referred to in these Letters Patent and making part of the same

To all whom it may concern:

Be it known that I, GEORGE WILKINSON, of the city and county of Providence and State of Rhode Island, have originated a new Design in articles of silver and plated ware for Fancy Spoon and Fork Work, of which the accompanying photograph, with this specification, is a full and complete description, that is to say, the articles of fancy spoon and fork work, substantially as shown in the said photograph.

Claim.

The design for fancy spoon and fork work, substantially as herein set forth.

Witnesses: GEO. WILKINSON

JOHN F. P. LAWTON,
THEODORE A. BARTON
